UNITED STATES PATENT OFFICE.

OSCAR PECK SMITH, OF WORCESTER, MASSACHUSETTS.

LIGHT-SHIELD.

1,387,200.

Specification of Letters Patent. Patented Aug. 9, 1921.

Application filed November 13, 1920. Serial No. 423,972.

To all whom it may concern:

Be it known that I, OSCAR P. SMITH, a citizen of the United States, and a resident of Worcester, county of Worcester, and 5 State of Massachusetts, have invented a new and Improved Light-Shield, of which the following is a full, clear, and exact description.

This invention relates to improvements in 10 light shields, an object of the invention being to provide an improved device of this type in the form of a strip which may be attached around the edge of a door frame to prevent light from passing through any 15 cracks or crevices caused by the loose mounting of the door within the frame.

A further object is to provide a strip primarily designed to keep undesirable light out of a dark room such as commonly used 20 by photographers, which may be temporarily attached to a door frame without permanent scarring of the wood-work.

A still further object is to provide a device of the character stated, which will be 25 simple and practical in construction, inexpensive to manufacture, and yet one which will efficiently perform the function for which it is intended.

With these and other objects in view, the 30 invention consists in certain novel features of construction and combinations and arrangements of parts as will be more fully hereinafter described and pointed out in the claims.

35 In the accompanying drawings:

Figure 1 is a view in elevation of a door frame and a door, showing my improved 40 strips in place.

Fig. 2 is an enlarged view in section on the line 2—2 of Fig. 1.

Fig. 3 is a perspective view of one of the strips.

Fig. 4 is a fragmentary perspective view 45 illustrating the different colors of the two faces of my improved strip.

1 represents a door frame to one side of which an ordinary door 2 is hingedly connected as shown at 3. 4, 4 represent vertical strips of molding secured to the door frame 50 and limiting swinging movement of the door in one direction.

My improved strip 5 is preferably made of cardboard or some similar light, flexible material, and is in the form of a narrow 55 strip having a longitudinal fold line 6 adjacent one edge. Suitable indicia such as 7

may be provided to designate the manner in which the strip is to be folded. That side of the strip upon which the indicia are printed, is preferably white and shiny so that it 60 readily reflects light falling upon it, while the reverse side of the strip is red, and acts as an extra protection to prevent actinic rays of light from passing therethrough.

The narrow edge of the strip which is 65 folded back and which I designate as 8, is preferably cut away at one end as shown at 9.

The strips are applied by bending slightly on the line 6 and gluing the edges 8 to the 70 molding strips 4, so that the free edges of the body portions of the strips rest lightly against the door as shown clearly in Fig. 2.

The end of the edge 8 of one strip will abut against the edge 8 of an adjacent strip, 75 the cut away portion 9 permitting the body portions of the strips to overlap as shown at 10, preventing the entrance of light between the two strips. The edges 8 may be gummed if desired, so that the strips can be readily 80 attached to the door frame.

If the strips are applied to the outside of a dark room door, the red side of the strip is located against the door, and if on the inside, the shiny surface is located against the 85 door as will be readily understood.

To remove the strip or strips it is merely necessary to tear them off, and with warm water to wipe off such glue or cardboard as still adheres to the door frame. I thus overcome one disadvantage common in such devices in that by using my strips the door is not scarred permanently.

Various slight changes and alterations might be made in the general form of the 95 parts described without departing from my invention, and hence I do not wish to limit myself to the precise details set forth, but shall consider myself at liberty to make such slight changes and alterations as fairly 100 fall within the spirit and scope of the appended claims.

What I claim is:

1. As a new article of manufacture, a light excluding strip attachable to a closure 105 frame to prevent light from entering between the closure and frame, said strip being formed of cardboard treated to present a light reflecting and light absorbing surface, said strip having a longitudinal fold line 110 adjacent one edge, and means for attaching the strip to a closure frame.

2. As a new article of manufacture, a light excluding strip attachable to a closure frame to prevent light from entering between the closure and frame, said strip being formed of cardboard treated to present a light reflecting and light absorbing surface, said strip having a longitudinal fold line adjacent one edge, and having adhesive material on one face thereof between the 10 fold line and the adjacent edge.

3. The combination with a closure and a closure frame, of a plurality of light excluding cardboard strips treated to present on one side a light reflecting surface and on

their other sides surfaces adapted to absorb 15 actinic rays of light, said strips bent along longitudinal lines to provide narrow edge portions and relatively wide body portions, adhesive material securing the edge portions to the frame, the free edges of said body 20 portions being held by their own resiliency against the closure, said edge portions being recessed adjacent the ends of the strips whereby the ends of the narrow edge portions 25 may abut and the ends of the body portions overlap.

OSCAR PECK SMITH.
